UNITED STATES PATENT OFFICE.

LLEWELLYN R. JONES, OF BELLEVILLE, ONTARIO, CANADA, ASSIGNOR OF ONE-
FOURTH TO CHARLES A. BADGLEY, OF BELLEVILLE, ONTARIO, CANADA.

WRINGER AND CLAMP THEREFOR.

1,373,965.

Specification of Letters Patent.

Patented Apr. 5, 1921.

Application filed April 5, 1920. Serial No. 371,526.

To all whom it may concern:

Be it known that I, LLEWELLYN R. JONES, a subject of the King of Great Britain, residing at Belleville, in the Province of Ontario and Dominion of Canada, have invented new and useful Improvements in Wringers and Clamps Therefor, of which the following is a specification.

This invention relates to clothes wringers and has particular reference to a clamping means for securely attaching the wringer to a tub, sink or other support.

One of the objects of the invention is to provide a simple and practical clamping means for this purpose comprising a clamping frame pivotally secured by bolts to one side of the wringer frame and having means for swinging the clamping frame about its pivots to force the lower portion thereof into close engagement with a support.

The invention also aims to generally improve wringer clamping means to render them more practical, reliable and commercially desirable.

With these and other objects in view as will become more apparent as the description proceeds, the invention consists in certain novel features of construction, combination and arrangement of parts as will be hereinafter fully described, illustrated and claimed.

In the drawings,

Figure 1 is a rear elevation of my improved wringer and clamping means.

Fig. 2 is a side elevation showing the wringer secured to a support.

Fig. 3 is a bottom plan view of the wringer and clamp.

Fig. 4 is a fragmentary detail view of a portion of one of the wringer legs.

Referring in detail to the drawings by numerals, 1 designates as an entirety a wringer having side bars 2, the lower portions of which constitute the legs 3. The wringer carries the usual squeezing rolls 4 and operating mechanism therefor, generally designated 5. A top bar 6 connects the side bars forming therewith a frame for the movable members of the wringer.

In the preferred embodiment of my improved clamping means for the wringer 1, I provide a clamping frame 6' having parallel side bars 7 which are connected at their lower ends by a base or clamping bar 8.

This bar 8 is rigidly secured to the lower

terminal faces of the legs or side bars 7 and has its inner edge concaved and beveled intermediate its ends as indicated at 9. Bolts 10 extend transversely through the frame bars 2 of the wringer and through the side bars of the clamping frame as shown. The heads 11 are counter-sunk in the frame bars 2 to prevent the bolts turning and each bolt is threaded to carry a wing nut 12 to tighten the clamping frame on the main frame. Washers 13 are preferably interposed between the nuts and the legs 7.

The side bars 2 of the wringer frame are recessed along their rear edges adjacent their lower ends as indicated by the numeral 13' to accommodate a tub or other support to which the wringer is to be secured. To give to the clamping frame an inclination downwardly toward the lower ends of the side bars 2, I form each of the side bars with an inclined face 14. The fastening and pivot bolts 10 extend centrally through the faces 14 so that the clamping frame has a bearing upon said faces when drawn thereagainst by the nuts 12.

To supplement the nuts 12 in clamping the frame tightly in engagement with a support, I provide cam levers 15 which are pivoted as at 16 to the clamping frame to engage wear plates or buttons 17 on the cross bar 18 secured to the side members 2 of the wringer frame. A bar or rod 19 connects the two cam levers 15.

In operation, the legs 3 are disposed on the inner side of a tub, sink or other support and the lower portions of the clamping frame legs on the outer side thereof. After this has been done, the nuts 12 are tightened to draw the wringer frame and clamping frame together to engage the clamping bar 8 of the clamping frame as tightly as possible with the support and then the cam levers 15 are swung into operative position to further tighten the clamp to insure a firm mounting of the wringer.

From the foregoing description taken in connection with the accompanying drawings, it will be obvious that by providing the inclined faces 14 and securing the clamping frame to the wringer so as to have a bearing on these inclined faces that the clamping frame may be thrown into close engagement with any tub or support to firmly secure the wringer thereon.

While I have shown and described the pre-

ferred embodiment of my invention, it will be clearly understood that I do not wish to be limited to this construction, but may make such changes as will fall within the scope 5 and spirit of the invention as claimed.

What I claim is:

In combination with a wringer including side bars formed in their rear edges at their lower ends with support receiving recesses, 10 the side bars being also provided on their rear edges adjacent the upper ends of said recesses with inclined bearing faces, bolts extending through the side bars centrally to said inclined bearing faces, a clamping 15 frame rockably associated with said side bars and having legs through which said

bolts extend, wing nuts threaded on said bolts to bind the clamping frame against said bearing surfaces, a clamping bar connecting the lower ends of the clamping legs 20 and projecting therebeyond toward the vertical walls of said support receiving recesses, a transverse bar connecting said side bars near the upper ends thereof, cam levers pivoted upon the upper ends of the legs of the clamping frame and engageable with said last named bar, whereby to tilt the clamping frame upon said bolts, and a rod 25 connecting said levers and serving as a handle.

In testimony whereof I affix my signature. 30
LLEWELLYN R. JONES.
